HENRY CAPEL LOFFT HOLDEN, OF LONDON, ENGLAND.

INTERNAL-COMBUSTION ENGINE.

SPECIFICATION forming part of Letters Patent No. 622,047, dated March 28, 1899.

Application filed December 28, 1897. Serial No. 664,146. (No model.)

To all whom it may concern:

Be it known that I, HENRY CAPEL LOFFT HOLDEN, a citizen of Great Britain, residing at The Eaves, Belvedere, and of Royal Arsenal, Woolwich, London, in the county of Kent, England, have invented certain new and useful Improvements in the Construction of Internal-Combustion Engines for Propelling Carriages, Cycles, and Boats, of which the following is a full and complete specification, such as will enable those skilled in the art to which it appertains to make and use the same.

My invention relates to improvements in the construction of what are usually termed "internal-combustion" engines, the working piston or pistons of which are actuated by the explosion of a mixture of volatilized or gaseous hydrocarbons and air in suitable proportions.

My invention has reference particularly to such engines of the above description as are used and can be employed for propelling carriages, cycles, and boats.

In the accompanying drawings, Figure 1 is a plan view of the main part of an engine provided with my improvements. Fig. 2 is a part elevation and part section of one of the cylinders. Fig. 3 is an elevation of a part of one of the end pieces, showing the arrangement for simultaneously opening the exhaust-valves; and Fig. 4 is a plan view of the same.

The reference-letters in each figure refer to the same or corresponding parts in the other figures.

The engine is constructed of two metallic tubes A A, which may be water-jacketed or not, as necessary or desired. Such tubes are preferably constructed of steel, though I do not desire to limit myself to that material, and are of suitable mechanical strength for the stresses to which they will be subjected in working. Each of the tubes A A forms a working cylinder, so that each tube comprises two working cylinders, and thus the two tubes A A together comprise four working cylinders.

In each of the tubes A A are two pistons, one at each end of each tube, one of these pistons being shown at N in the section part of Fig. 2. The piston N is rigidly connected to another similar piston, similarly situated at the other end of the tube, by the piston-rod

D, which rod has a hole S through the center of its length at right angles to the axis, and through this hole the cross-head bar G passes. 55 This cross-head bar G also passes through the piston-rod, connecting the two pistons in the other tube. Thus the two systems of pistons, one in each of the tubes A A, are moved simultaneously, being connected together by 60 the aforesaid cross-head bar G.

In order that the cross-head bar G may move backward and forward in the tubes A A, a slot E is cut in each side of each of the tubes A A and is of the same width as the diameter of the 65 cross-head bar G. The slots E are opposite and parallel to one another and of suitable length for the working stroke of the engine. The cross-head bar G passes through all of the slots, and the latter act as a guide for the 70 movement of the cross-head bar.

To the outer ends of the cross-head bar G, which ends project beyond the tubes A A on either side are attached by bearing-sleeves the two connecting-rods Q Q, which are attached to the crank or cranks of the main shaft of the engine in the usual manner and for the usual purpose of rotating it.

In order to exclude dust or foreign substances from the tubes A A, which form the 80 working cylinders, segments of tube F may be arranged so as to cover the slots E E and to work backward and forward with the cross-head-bar G, which passes through them. The segments F F may be used to protect all of 85 the slots E E or only the two outside ones, as shown in Fig. 1.

The outer ends of the tubes A A are closed by suitably-shaped blocks of metal B B, in which are situated the inlet-valves I and the 90 exhaust-valve H. The ends of the tubes A A are bedded in the blocks B B in such a manner as to obtain a suitable joint to withstand the pressure caused by the explosion, and the aforesaid ends may be screwed or shrunk 95 into recesses in the blocks or may be, as shown in the drawings, held in position by two or more tie-rods C C, passing through holes in the blocks and holding the whole system of tubes and blocks firmly together.

In Fig. 2 is shown a section through a part of the block B, illustrating one of the four sets of exhaust and admission valves. The exhaust-valve H is normally kept closed by

the action of the spring P, except at such times as the valve is forced downward and off its seating by the pressure of the arm J, which arm is itself actuated in a manner to be hereinafter described. By the opening of the valve II the waste gases after the explosion and working stroke are allowed to escape from the working cylinder into the passage R and thence to the external air.

10 The inlet-valve I is situated opposite the exhaust-valve H. It is held normally closed by the action of gravity or by means of a light spring, as is the usual custom, or by the combined action of gravity and a spring. 15 The valve I is lifted by the partial vacuum produced by the movement of the piston N on its forward stroke, and the vacuum so produced draws in the necessary explosive mixture from the source of supply through the 20 passage O, which is connected to the source of supply by means of pipes in the usual manner. On the return of the piston N the valve I is closed and the explosive mixture compressed into the space in the tube A behind the piston N and between the piston N and the block B. As the piston moves forward again the compressed mixture is fired by one or other of the well-known electrical or mechanical means in common use for this 25 purpose, such as the electric spark, heated tube, or wire. These firing devices are well known and do not form a part of my invention. I consequently do not describe them in detail or illustrate them in the drawings, 30 but employ them in connection with my invention as may be most suited for the purpose in hand.

The levers or arms J J are mounted on short shafts or arbors journaled in the blocks B B, 40 and they carry also pieces K K, which embrace and are actuated by cams or eccentrics L L, mounted on a shaft M in such a manner that when said shaft is rotated the ends of the levers or arms J J are raised and depressed, thereby actuating the exhaust-valves H II. The shaft M is journaled in the end blocks B B and is carried beyond one of them in the direction of the crank-shaft, to which it is attached by means of intermediate mechanism, comprising gear-wheels or equivalent devices, in such a manner that its angular velocity is only one-half that of the crank-shaft actuated by the connecting-rod Q Q. The rotation of the shaft M by the crank-shaft of the engine at only one-half the angular velocity of the latter thus causes the exhaust-valves H II to be opened in the proper succession and at the right moment.

The engine works on the Otto or four-cycle 60 principle, which is well known, and since the four cylinders work in succession to one another then it follows that the cross-head bar G and through it the connecting-rods Q Q are continuously acted upon by a working stroke 65 in either direction.

In some of the applications of my invention—for instance, when it is used for prop-

elling cycles—it is desirable to have some means not only to prevent the explosive mixture from entering the cylinders, but also to prevent the air which is drawn into the cylinders from being compressed, and thereby causing an increased resistance in propelling the cycle. The arrangement I adopt for the purpose just stated is shown in Figs. 3 and 4. 70 To effect this, a small shaft W is arranged parallel to and above the shaft M and is also journaled in the end pieces B B. This shaft W carries at either end two cam-pieces V, which lie between the vertical arms of two 75 L-shaped levers T and U. The vertical arms are pulled toward each other by a spring X. These lever-arms T and U are pivoted on and are free to revolve around the same arbor as the lever J is fixed to, and as the horizontal 80 arms of both levers T and U are interposed between the lever J and the spindles of the valves H H it follows that when the lever J rocks under the action of the shaft M, as before described, it will depress the arms of the 85 levers T and U and through them the valves H H.

It will be understood that if the shaft W be turned through one quarter-turn, or ninety degrees from the position shown in the drawings, the vertical arms of the levers T and U will be forced outward and the horizontal arms downward, so that they depress the exhaust-valves, thereby allowing a free passage 90 to the air both into and out of the cylinders. 95

It will be understood that while the improvements set forth in the claims have been described as embodied in precise forms I contemplate such changes in the arrangement and construction of the parts as may be necessary for the best application of my improved engine to the purpose in view whether it be a carriage, a cycle, or a boat that is to be propelled, and I therefore reserve the right to all such variations and modifications as properly fall within the spirit and scope of my invention and improvements.

Having fully described my invention, I claim as new and desire to secure by Letters Patent—

1. An internal-combustion engine of the class described, comprising four tubes arranged in pairs and provided with slots in their opposite sides, two pistons mounted in each of said tubes and connected by piston-rods, means for connecting said piston-rods consisting of a cross-head bar passing through the piston-rods and through said slots, end blocks by which the ends of said tubes are closed, said blocks being provided with ports or passages and valves for controlling the same, and levers or arms J adapted to actuate said valves, said levers or arms being journaled upon a shaft or arbor which is provided with dogs, and a main shaft mounted parallel with said tubes and provided with cams which operate in connection with said dogs, and auxiliary devices for controlling said valves, comprising L-shaped levers T,

U, pivotally mounted upon the same shafts as said levers J, and having arms interposed between said levers J, and the stems of said valves, and arms separated by cams mounted 5 on a shaft parallel to said main shaft, and means straining said cam-separated arms toward each other and mounted thereon, substantially as shown and described.

2. In an internal-combustion engine of the 10 class described, the combination, with the projecting valve mechanism, of the arms or levers J carried upon a rock-shaft and adapted to actuate said valve mechanism, means for operating said rock-shaft, the L-shaped 15 levers T and U arranged with respect to the arms or levers J, and the shaft W carrying cam-pieces adapted to operate with respect to the L-shaped levers, substantially as and for the purpose set forth.

20 3. In an internal-combustion engine of the class described, the combination, of the projecting valve mechanism, the L-shaped levers T and U, and the shaft W carrying the cam-pieces adapted to operate said levers, substantially as and for the purpose set forth.

25 4. In an internal-combustion engine of the class described, the combination of the projecting valve mechanism, the arms or levers J arranged upon rock-shafts provided with 30 pieces or dogs, the shaft M carrying cams or eccentrics adapted to engage said pieces or dogs, the L-shaped levers T and U mounted upon the same shaft as the arms or levers J, and with respect to the latter, and the shaft 35 W carrying arms adapted to engage said L-shaped levers, substantially as and for the purpose set forth.

5. In an engine of the character described, comprising two or more tubes each having 40 pistons mounted therein connected by piston-

rods, and blocks closing the ends of the tubes, valves in said end blocks and valve mechanism controlling said valves, and comprising levers J mounted on arbors journaled in said end blocks and bearing cams or dogs, a shaft 45 mounted parallel with said tubes and also bearing cams or dogs engaging therewith, and supplemental L-shaped levers T, U, pivotally mounted upon the same arbors as said levers J, and bearing-arms interposed between 50 said levers J and the stems of the valves and arms separated by cams journaled upon a shaft U journaled in said end blocks, and means connected with said cam-separated arms and straining them toward each other, 55 substantially as shown and described.

6. In an engine of the character described, exhaust-ports communicating with the cylinders and valves adapted to close and open the same and controlled by lever-arms mounted 60 in arbors bearing cams operating in connection with cams on a shaft geared to the crank-shaft of the engine, and supplemental L-shaped arms pivotally mounted on said arbors, and having arms interposed between 65 the valve-stems and said first-mentioned lever-arms, and arms separated by cams mounted on another shaft and means connected with said last-mentioned arms straining them toward each other, substantially as shown and 70 described.

In testimony that I claim the foregoing as my invention I have signed my name, in presence of the subscribing witnesses, this 3d day of December, 1897.
